United States Patent

Des. 240,761
Patented July 27, 1976

240,761

TABLE LAMP

Bruce W. Medford and Mary A. Medford, both of 852 Hopwood Lane, Virginia Beach, Va. 23455

Filed Mar. 20, 1975, Ser. No. 560,246

Term of patent 14 years

Int. Cl. D26—05

U.S. Cl. D48—20 R

FIG. 1

FIG. 2

FIG. 1 is a front elevational view of a table lamp embodying our new design;

FIG. 2 is a left side elevational view thereof; and

FIG. 3 is a top plan view thereof.

We claim:

The ornamental design for a table lamp, as shown.
